UNITED STATES PATENT OFFICE.

AUGUSTIN J. CHEVRETTÉ, OF WORCESTER, MASSACHUSETTS, ASSIGNOR TO THE CROMPTON & KNOWLES LOOM WORKS, OF WORCESTER, MASSACHUSETTS, A CORPORATION OF MASSACHUSETTS.

WEFT DETECTOR FOR LOOMS.

Application filed November 19, 1925. Serial No. 70,161.

This invention relates to improvements in weft detectors for looms and it is the principal object of the invention to provide a detector capable of use with bobbins which 5 may be improperly disposed in the shuttle so that slight angular misplacements of the shuttle may not interfere with the effective operation of the detector.

In my co-pending application, Serial No. 10 38,072, filed June 18, 1925, I have shown a feeler case slidable in a relatively fixed bed and having on the rear end thereof a pair of swinging toothed yarn impinging detectors which are located between a pair of 15 yarn penetrating detectors. In that application each yarn impinging toothed detector is provided with a lateral arm the rear face of which is normally in contact with a fixed stop and the forward face of which is normally pressed against the stop by yielding means. It is found that the pressure between the lateral arms and the stop prevent free and proper movement of the yarn impinging detectors and it is a further object 20 of my present invention to secure freedom of movement of the detectors by controlling the same by a transmitter having a forked end on each side to receive the lateral arm of the detector. The fingers of the fork can 25 be pressed together when desired to compensate for wearing between said fingers and the detector arm.

In detectors of the general type to which the present invention relates it has been 30 found that the rod or transmitter which controls the swinging detector is subject to undesirable bending and it is a further object of my invention to prevent this bending by confining the rod on all four sides throughout 35 the greater portion of its length.

A more particular object of the invention is to construct the slide on which the detectors are mounted independently of the transmitter, the latter being outside of the 40 slide and being assembled in position independently of the slide, thus simplifying assembly of the detector.

Detectors of the type set forth herein have usually been provided with a slide having 45 an ear extending upwardly therefrom through which a guide pin extends. The pin has customarily been formed with a head against which the ear is forced by spring pressure and it has always been necessary

to change the position of the pin whenever 55 an adjustment is necessary in the detector. It is a still further object of my invention to render manipulation of the guide pin unnecessary by omitting the head usually 60 formed thereon and providing the transmitter or control rod for the detector with a screw or other form of stop sufficiently strong to position a slide under action of the spring which surrounds the guide rod.

With these and other objects in view 65 which will appear as the description proceeds, my invention resides in the combination and arrangement of parts hereinafter described and set forth in the claims.

In the accompanying drawings wherein 70 one form of my invention is shown,

Fig. 1 is a top plan view of a detector showing the same moved forwardly in contact with a full bobbin,

Fig. 2 is a side elevation taken in the direction of arrow 2, Fig. 1, certain parts being in section,

Fig. 3 is an enlarged top plan view of the detector slide and supporting bed therefor, the cover of the slide being removed to 75 show the interior thereof and the detectors being in normal position prior to contact with the bobbin.

Fig. 4 is a view similar to Fig. 3 but with the parts moved to indicating position after 80 contact with a supply of weft insufficient for continued weaving,

Fig. 5 is an enlarged rear elevation of the detector taken in the direction of arrow 5, 85 Fig. 3, and

Figs. 6 and 7 are vertical transverse sections taken respectively on lines 6-6 and 7-7 of Fig. 3 and looking in the direction of the arrows.

Referring to Fig. 1 it will be seen that I 90 have provided a detector stand 10 having an arm 11 in which reciprocates a vertical plunger 12. An actuating lever 13 is loosely pivoted as at 14 to the plunger and rises and falls with the latter during the normal operation of the loom. One end of said lever 13 extends in a slot 15 formed in arm 11 and across a hole 16 formed in said arm 11. The other end of said actuating lever is connected with a rod 17 extending upwardly to 100 the replenishing mechanism.

A shaft 18 is freely rotatable in spaced bearings 19 and 20 extending forwardly

from the stand 10. One end of said shaft has secured thereto a finger 21 pivotally connected at the upper end thereof to a controller pin 22 which extends through the hole 16 and is normally under the actuating lever 13. A collar 23 secured to shaft 18 receives one end of a coiled spring 24 the other end of which is received by bearing 20. A second finger 25 is secured to the shaft 18 and extends upwardly therefrom for engagement with a transmitter to be described. When finger 25 is rocked to the left as indicated in Fig. 2, controller pin 22 will be withdrawn from under the actuator lever so that the latter may descend without causing movement of the rod 17. When said finger 25 is not moved to the position shown in Fig. 2 the controller pin 22 remains under the actuating lever and as the latter descends rod 17 is depressed to give an indication to the weft replenishing mechanism. The mechanism thus far described is substantially the same as that set forth in Patent No. 1,030,748.

25 The detector comprises a bed 30 mounted on a stud 31 secured to the stand 10 and said bed has mounted therein for back and forth motion a slide 32 to which is secured an ear 33 through which extends a guide pin 34. 30 The latter is mounted in a cap 35 secured to the bed 30 and is held in position by a set screw 36. A spring 37 is interposed between the cap and the ear and serves to hold the slide 32 yielding rearwardly. 35 Said slide as shown in Figs. 3 and 4 is provided with a pair of rearwardly extending spaced yarn penetrating detectors 38 between which are mounted a pair of toothed yarn impinging detectors 39 pivoted to the slide as at 40. Said detectors 39 move in parallel planes as shown in Fig. 6 and are normally so placed that their rearmost extremity is slightly forward of the line joining the rear ends of detectors 38. Each detector 39 is provided with a laterally extending arm 41 having a depending finger 42 shown in Figs. 2, 5, and 6. That portion of the detector already described is similar to the detector set forth in my aforesaid pending application.

50 My present invention relates more particularly to the control mechanism for the swinging detectors 39 and the finger 25. In carrying out my invention I provide the bed 30 with parallel slots 50 extending under the slide 32. I further provide a transmitter 51 formed with a cross bar 52 which is extended to the right as shown in Figs. 3 and 4 to receive a stop screw 53 held adjustably with respect to the transmitter 51 and positioned to engage the bed 30. The cross bar 52 receives the pressure of the finger 25 and the transmitter is thus held in rear position by the spring 24 under normal conditions. The transmitter 51 is provided with spaced par-

allel arms 54 which are received by the slots 50 and lie under the slide 32. The rear ends of the arms are oppositely bent as at 55 and terminate in rear prongs 56 and front prongs 57, respectively, between which extend the depending fingers of arms 41. Said prongs can be pressed together slightly to compensate for wear between the same and the fingers 42 on arms 41.

55 The slide 32 is normally held yieldingly in rearward position by spring 37 and as the arms 41 engage the rear prongs 56, said arms are restrained against further backward movement with the result that detectors 39 are held in the position shown in Fig. 3. When a bobbin having sufficient 60 yarn engages the detectors 39 they will be restrained against angular motion, causing arms 41 to engage forward prongs 57 as the lay advances. Cross bar 52 will therefore move the finger 25 from its normal full line position shown in Fig. 4 to the dotted line position in said figure and the full line position shown in Figs. 1 and 2, with the result 65 that pin 22 will move from under lever 13. When insufficient yarn is present, however, the detectors 39 will be unrestrained and as slide 32 moves forwardly due to contact between the detectors 38 and a bare bobbin or one having an insufficient supply of weft 70 thereon, the spring 24 will hold the transmitter rearwardly, the fingers 57 causing movement of the detectors 39 from the position shown in Fig. 3 to that shown in Fig. 4. The transmitter thus remains at rest and the controller pin 22 will remain under the actuating lever 13 to give an indication, as previously described.

75 From the foregoing it will be seen that I have provided a detector so arranged that the connection between the swinging detectors and the transmitting element is outside the slide 32 so that it may be conveniently altered to compensate for wear and that the parallel sides of the transmitting element are confined in a slot under the slide so as to be supported against lateral bending under pressure of spring 24. It will also be seen that the transmitter is separate from the slide which carries the detectors so that the device may be readily assembled and it will further be seen that the ear 33 is not resisted in its rear movement by any means other than the screw 53.

80 Having thus described my invention it will be apparent that changes and modifications may be made therein by those skilled in the art without departing from the spirit and scope of the invention, and I do not 85 wish to be limited to the details herein disclosed but what I claim is:

85 1. In a weft detector mechanism for looms, a support, a slide movably mounted thereon, a yarn penetrating detector fixed to the slide, a yarn impinging detector mounted on the 90

slide for lateral movement, an arm extending from the movable detector and terminating at a point outside the slide, means to hold the slide yieldingly in rearward position, 5 a transmitter located entirely outside the slide and having a forked end spaced from said slide to receive the arm of the movable detector, yielding means to hold the transmitter in rearward position, and an 10 indicating mechanism effective to indicate exhaustion of weft when the movable detector moves laterally with respect to the slide upon forward movement of the latter:

2. In a weft detector mechanism for 15 looms, a support, a slide mounted for movement on the support, a detector mounted

on the slide for relative movement with respect thereto, actuating mechanism, a controller for the actuating mechanism, and a transmitter operatively connected to the 20 detector and the controller guided for longitudinal movement in the support and external to the slide, the operative connections between the detector and the transmitter being offset laterally from the slide to be 25 readily accessible and including a fork the prongs of which may be drawn together to compensate for wear.

In testimony whereof I have hereunto affixed my signature.

AUGUSTIN J. CHEVRETTE.
